UNITED STATES PATENT OFFICE.

JOHN T. H. MITCHELL, OF CHICAGO, ILLINOIS.

ADVERTISING DEVICE.

1,054,018.

Specification of Letters Patent. Patented Feb. 25, 1913.

Application filed April 29, 1909. Serial No. 492,888.

To all whom it may concern:

Be it known that I, JOHN T. H. MITCHELL, a citizen of the United States, and a resident of Chicago, Cook county, and State 5 of Illinois, have invented a certain new, useful, and Improved Advertising Device, of which the following is a full, clear, and exact description, such as will enable others skilled in the art to which it appertains to 10 make and use the same.

My invention relates to advertising devices and has particular reference to improvements in advertising devices of the class adapted to be sent through the mails, 15 without an envelop, yet partaking of the character of personal, individual communication.

The object of my invention is to provide an improved advertising device in the nature of a personal letter-carrier or bearer, 20 but constituting its own closure or envelop and having a part formed to be detached and to serve as a return card or postal card.

Other objects of my invention will appear hereinafter.

My invention consists generally in an advertising device or folder comprising a substantially rectangular ungummed sheet of cardboard scored upon two transverse lines 30 and thereby formed into upper, lower and intermediate flaps. Said lower flap being detachable from the remainder and constituting a return postal card and the upper flap being adapted to fold over said intermediate and lower flaps and formed to conceal part of the face of the lower flap, exposing to view only that part thereof which bears the name and address of the person for whom the device is intended.

My invention will be more readily understood by reference to the accompanying drawings, forming a part of this specification and in which:

Figure 1 is a perspective view of an advertising device embodying my invention; Fig. 2 is a similar view showing the device partly folded; Fig. 3 is another perspective view showing the device as it appears when ready for the mail; and Fig. 4 is a sectional view, enlarged, on the line X—X of Fig. 3.

My invention is capable of considerable modification and is not limited to the specific proportions or form shown in the drawings; however, in all forms of my invention I prefer that the device shall be

of substantially the size and shape of ordinary commercial letter paper and when folded, as shown in Fig. 3, shall present the appearance of an envelop.

As shown in Fig. 1, the device comprises 60 a sheet, A, of thick paper or heavy cardboard. This sheet is scored on the line, a, and is also scored or partly severed or perforated on parallel line, b. The scorings divide the sheet into the two wide portions, 65 C and D, and the narrower portion, E. The latter is preferably the top of the sheet and bears, on its inner surface, the letter head, F, of the advertiser. The remainder of the flap, E, and the surface of the flap, D, serve 70 to receive the letter or communication, G, and when desired, the name, G', of the recipient may be written or printed on one of the flaps, E, D. The inner surface, C', of the lower flap, C, is printed as a post card 75 and bears the name, F', of the advertiser or an agent or dealer to whom the advertiser desires the return to be made. In the corner of the post card is the stamp, H. The line of perforations or the scoring, b, adapts 80 the fold, C, to be easily detached from the remainder of the sheet. The outer surface, C'', of the flap, C, bears a printed return communication, G'', and the name, G''', of the recipient. The proportions of the sheet 85 are such that when the flap, C, is folded onto the inner face of the flap, D, the flap, E, may be folded down over the flap, C; the flap, E, is secured in such position by a sticker or seal, I, and it will be noted that 90 the flap, E, serves to cover the communication, G'', on the back of the postal card portion of the device, leaving exposed only the name, G''', of the recipient. The latter 95 therefore serves as the address of the device as a whole and the device is prepared for the mails by affixing the stamp, H', to the outer face of the flap, E. When thus sealed and made ready for the mails the device constitutes an open ended envelop which because all of its parts may be inspected will 100 pass through the mails as third-class matter, i. e. at one cent postage.

The person to whom the device is addressed on receiving same breaks the seal, I, 105 and opening the sheet has presented to him the communication appearing upon the inner face thereof. If interested in the communication, in the articles advertised, or in the subject of inquiry, he, the recipient, has 110

only to tear off the post card portion, C, and deposit same in the mail. The recipient is not required to sign his name or give his address; as a rule is not even required 5 to enter remarks on the back, C'', of the part, C.

It will now be obvious that my device constitutes an extremely valuable means for use in advertising and for securing both the 10 initial attention of the recipient and a reply indicating his decision in the matter called to his attention. The outer face of the flap, E, and the back or outer surface of the flap, D, afford space for attractive pictures or 15 other devices which serve as initial attention attractors; and in practice I prefer to combine with this invention that other invention which is shown and claimed in my Letters Patent No. 861,747 dated July 30th, 20 1907.

Having thus described my invention, I

claim as new and desire to secure by Letters Patent:

A folder or advertising device comprising a substantially rectangular sheet of 25 cardboard scored transversely to form intermediate and lower flaps of given width and an upper flap of less width, said lower flap being easily separable from the remainder and constituting a reply postal card, 30 and said upper flap, when the device is folded, serving to conceal all the printed matter on the lower flap except the name and address of the recipient.

In testimony whereof, I have hereunto set 35 my hand, this 26th day of April, 1909, in the presence of two subscribing witnesses.

JOHN T. H. MITCHELL.
